UNITED STATES PATENT OFFICE.

EMIL HOTTINGER, OF PHILADELPHIA, PENNSYLVANIA, ASSIGNOR TO HESS-BRIGHT MANUFACTURING COMPANY, OF PHILADELPHIA, PENNSYLVANIA, A CORPORATION OF DELAWARE.

EXPANDING ARBOR.

1,346,890.

Specification of Letters Patent. Patented July 20, 1920.

Application filed June 30, 1919. Serial No. 307,594.

To all whom it may concern:

Be it known that I, EMIL HOTTINGER, a citizen of the United States, residing at Philadelphia, in the county of Philadelphia and State of Pennsylvania, have invented 5 certain new and useful Improvements in Expanding Arbors, of which the following is a specification.

This invention relates to arbors for supporting annular pieces of work, particularly those which are to be machined or finished in some manner upon the outer surfaces, an object of the invention being to form such an arbor with a closed chamber and locate 10 an expander therein in such manner that the working parts are completely housed within such closed chamber. Since these arbors are frequently used in positions where the work carried by them is subjected to a cooling bath, it is quite necessary 15 to protect the working parts. In other instances where the work is performed in a practically dry condition, such working parts should be protected from chips and abrasives which otherwise interfere with the proper working of the parts and prove destructive to the device as a whole.

The drawings accompanying this specification illustrate the invention, in which 20 drawings—

Figure 1 is a view partly in central longitudinal section and partly in elevation of my improved arbor, showing the same in its work clamping or holding position.

Fig. 2 is a cross section taken on a plane at about line 2—2 of Fig. 1, and

Fig. 3 is a cross section through the shell and the expander plug at about the lines 3—x and 3—y respectively, illustrating the 25 manner of assembling these parts.

My improved arbor in the form illustrated, is intended to be mounted between centers and to be driven by a live spindle of some suitable machine, as for instance a 30 grinding machine. The centers may if desired engage permanent parts of the arbor casing sockets 19', 20', being shown for such purpose.

The shell 5 of the arbor is formed with 35 a hollow interior 6, and a substantial cylindrical external work receiving face 7. This face preferably has a slight taper, from the stop shoulder 8 to the outer end. Dotted lines show a piece of work 9 in position on

this face 7 and in engagement with the back stop or shoulder 8. By reference to the drawings it will be seen that the wall forming the shell of the casing is so formed that although it is unbroken it is nevertheless capable of circumferential expansion 40 and contraction, the expansion being caused by force applied from within, and the contraction resulting from the natural elasticity of the metal of the shell when relieved from such expanding force. A preferred mode of construction of this wall for affording this ability to expand and contract is the formation of a series of longitudinal external depressions 10 defining a plurality of outwardly extending ribs 11, 45 and longitudinal internal depressions 12, defining a plurality of inwardly extending ribs 13, the wall at the bottom of each of the external grooves being formed as an inwardly facing rib. It is upon the outer 50 faces of the ribs 11 that the cylindrical work received seat 7 is formed. Upon the inner face of the ribs 13, expander and engaging faces 14 are provided, these latter faces being formed on a taper for the engagement of the taper face 15 of the expander plug 16. The exterior of the plug is shown provided with a series of longitudinal grooves 17, defining a plurality of ribs 18, upon the crests of which is formed the 55 taper face 15.

The front end of the shell is shown provided with an integral closed end 19. A removable closure 20 is carried by the back end of the shell. A completely closed chamber 60 is thus provided within the shell in which the expander is inclosed and its ends are preferably normally free from the ends of the shell. From the foregoing it will be seen that within the chamber of the elastically 65 expandible arbor there are inclosed means active upon the walls of said arbor for expanding the same, such means being responsive to the impact of a blow upon the end of the arbor. In fact the expander means, the 70 taper plug in the present illustration, is moved toward either end of the arbor by the impact of a blow or succession of blows upon that end of the arbor.

When it is desired to apply a piece of work 75 to the arbor, as for instance a ring 9, the arbor is preferably placed in an upright position, for instance with the back end, repre-

sented by closure 20, resting upon a work bench, the ring is then slipped over the outer or front end of the arbor until it rests against the back stop shoulder 8, whereupon the arbor is raised a short distance from the work bench and either permitted to drop or forcibly brought in contact with some object, whereupon the expander plug moves inwardly and toward the end 20 thereby expanding the shell and consequently expanding the work seat 7. This movement also draws the work against the back stop. When it is desired to remove the work a reverse operation is performed, namely the arbor is again put in a vertical position, but this time with the front end, represented by the closure 19, directed downwardly, and a blow imparted to such end, as for instance by permitting the arbor to fall upon the work bench or other solid body as for instance a block of wood. It is the better practice to use some elastic striking body so that too heavy a blow will not be given or the end of the arbor injured. The blow on the end 19, particularly when this is in an upright position, brings the expander from its active to its idle position, permits the wall of the shell, by the influence of its own elasticity to assume its normal position, and at the same time causes the work to drop from the work seat. It is then merely necessary for the workman to reverse the position of the arbor upon the bench and place another ring in position and again perform the expanding operation.

In the form of the invention illustrated in the drawing it will be seen that the larger end of the expander plug is in the permanently closed end of the shell, that is the taper upon the crests of the ribs 13 and 18, namely the faces 14 and 15, taper from such closed end backwardly toward the end having the removable closure 20.

To enable the ready assemblage of the parts, in other words the insertion of such a plug into such a chamber, the grooves 12 are of sufficient dimensions at the back or open end of the shell to receive and permit the passage of the ribs 18, and the grooves 17 are also of sufficient dimensions to receive and let pass the ribs 13. This is illustrated in Fig. 3 which shows the parts at about the commencement of the insertion, the cross section of the shell being taken at about the plane of the line 3—*x* and the cross section of the plug being taken at about the plane of the line 3—*y* of such figure. Upon the completion of the insertion of the plug the crests of the ribs 18, assume a position in which they are of less radius than are the crests of the ribs 13, at any particular point, whereupon a slight rotation of the plug relatively to the shell of an angular distance of half the pitch distance will bring the parts from the angular position represented in Fig. 3,

to the position represented in Fig. 2, this latter being the normal working position of the expander plug. The parts are readily held in this working position by suitable spring pressed detents 21, mounted in a seat 70 in the plug, and having their outer ends formed to mate with the grooves 12.

The spring 22 is sufficiently strong to prevent displacement of the detents, but the engaging parts are so formed that the application of a slight amount of force will readily depress the detents and permit the disassembly when desired.

It will be apparent that changes may be made in the details of construction for the purpose of adapting my improved arbor to the various uses to which it will be put without departing from the spirit of my invention as set forth in the claims.

I claim as my invention:

85

1. The combination with an elastically expandable arbor provided upon its exterior with a work seat, there being a chamber within said arbor, of an expander located wholly in said chamber and capable upon its movement to expand the same and adapted to be moved by the impact of a blow upon the end of the arbor.

2. An expanding arbor, comprising a shell having elastic side walls, provided on the exterior with a work seat, the walls of the shell forming a closed chamber, and a weighted expander plug located in the chamber and adapted to act upon the elastic side walls for expanding the same and 100 the work seat.

3. An expanding arbor, comprising an elastically expandable shell and a reciprocatory expander located wholly within the shell and adapted upon its excursion to act 105 upon the shell for expanding the same, the parts being so organized that the impact of a blow upon one end of the arbor effects the excursion of the expander and the impact of a blow on the other end of the arbor 110 effects the recession of the expander.

4. An expanding arbor, comprising an elastically expandable shell and a reciprocatory expander located wholly within the shell, the parts being so organized that the impact of a blow upon either end of the arbor moves the expander toward such end.

5. The combination with an arbor having an elastically expandable wall provided upon its exterior with a work seat, of a reciprocatory expander located wholly within such wall, the parts being so shaped and organized that impact applied to one end of the arbor causes the expander to expand the wall at the work seat and impact applied to 125 the opposite end causes the expander to release such wall to the influence of its own elasticity.

6. An expanding arbor, comprising a shell having upon its exterior a work seat, its in- 130

- terior forming a closed chamber, of a reciprocatory expander inclosed within such chamber, the parts being so shaped and organized that impact applied to one end of the arbor 5 seats the work and expands the work seat and impact applied to the opposite end contracts the work seat and unseats the work.
7. An expanding arbor, comprising a shell having upon its exterior a work seat and a work stop at the back of the seat, the seat 10 tapering from such stop toward the front, the wall of such shell forming a closed chamber tapering from the front end toward the back end, and a similarly tapering 15 expander plug inclosed in said chamber and normally free of the ends thereof, the parts being so organized that the impact of a blow on the back end seats the work and expands the work seat and a blow upon the front end 20 of the arbor permits the walls to contract and unseats the work.
8. An expanding arbor, comprising a shell having upon its exterior a work seat and a work stop at the back of the seat, the seat 25 tapering from such stop toward the front, the wall of such shell forming a closed chamber tapering from the front end toward the back end, a similarly tapering expander plug inclosed in said chamber and normally 30 free of the ends thereof, the parts being so organized that the impact of a blow on the back end seats the work and draws the expander toward the back end, thereby expanding the wall and the work seat, and a blow upon the front end of the arbor withdraws the expander toward the front end 35 and permits the walls to contract and unseats the work.
9. An arbor having an expandible wall 40 provided with an exterior work receiving face, there being a chamber within such wall, the wall being unbroken throughout for closing such chamber, and a heavy taper expander plug freely-reciprocatory within 45 such chamber and adapted to move forward by its momentum and act upon the arbor wall for expanding the same upon arrest of momentum of the arbor.
10. An arbor having an expandible wall 50 provided with an exterior work receiving face, there being a chamber within such wall, the wall being unbroken throughout for closing such chamber, and a heavy taper expander plug freely reciprocatory within 55 such chamber and adapted to move toward either end of the arbor responsive to a blow upon such end.
11. An expandible arbor, comprising a shell having a substantially cylindrical exterior surface provided with longitudinal 60 ribs and grooves, the inside being provided with ribs opposite the bottoms of the exterior grooves and with grooves opposite the interior ribs, thereby forming an unbroken 65 elastically expandible wall, the crests of the

interior ribs being tapered, and a tapered expanding member located within the shell and adapted to engage the crests of the interior ribs for expanding the wall.

12. An expandible arbor, comprising a shell having a substantially cylindrical exterior surface provided with longitudinal ribs and grooves, the inside being provided with ribs opposite the bottoms of the exterior grooves and with grooves opposite the interior ribs, thereby forming an unbroken elastically expandible wall, the crests of the interior ribs being tapered and a tapered expanding member located within the shell and provided with ribs adapted to engage 80 the crests of the interior ribs for expanding the wall.

13. An expandible arbor, comprising a shell having a substantially cylindrical exterior surface provided with longitudinal ribs and grooves, the inside being provided with ribs opposite the bottoms of the exterior grooves and with grooves opposite the interior ribs, thereby forming an unbroken elastically expandible wall, the crests of the interior ribs being tapered, a tapered expanding member located within the shell and provided with ribs adapted to engage 85 the crests of the interior ribs for expanding the wall and means for preventing rotation 90 of the shell and expander.

14. An expanding arbor, comprising a shell adapted to expand responsive to internal pressure and to elastically assume its normal position upon release from said pressure, such shell having closed ends affording a closed chamber, and an expander member inclosed within said chamber and longitudinally movable therein and operative upon the walls to expand the same.

15. In a device of the character specified, the combination with a shell having ribs upon its interior and upon its exterior, the crests of the ribs on the exterior forming a substantially cylindrical work seat and the 110 crests of the ribs upon the interior forming a tapered chamber, the shell having an integral closure at the larger end of such chamber, a closure at the other end of the chamber, and an expander inclosed within the 115 shell having tapered ribs to engage the interior ribs of the shell for expanding the work seat.

16. An expanding arbor, comprising a shell having longitudinal ribs upon its exterior, the crests of said ribs forming a work seat and longitudinal ribs and grooves upon its interior, the crests of such ribs being tapered, the chamber of the shell being permanently closed at the larger end defined by 125 said taper, and an expander inclosed within such chamber, the surface of such expander being provided with a series of longitudinal ribs and grooves, the ribs of the expander being located in position to engage the ribs 130

- of the shell for expanding the same, and said ribs and grooves of the expander and the shell being respectively located in such relative positions that a slight rotation of 5 the expander brings its ribs between the ribs of the shell whereby the larger end of the expander may be inserted into or withdrawn from the chamber at the smaller end thereof.
- 10 17. An expanding arbor as defined in claim 16 having a closure for the smaller end of the chamber.
18. An expanding arbor, as defined in claim 16 having a closure for the smaller 15 end of the chamber, and spring pressed detents carried by the expander and adapted to enter the grooves in the shell for holding the expander in its operative position.
19. An expanding arbor, comprising a shell having upon its exterior a work seat 20 and a work stop at the back of the seat, the seat tapering from such stop toward the front, the front wall of the shell being integral with the side wall, the walls of such shell forming a closed chamber having tapering sides, and a similarly tapering reciprocal expander plug inclosed in said chamber. 25

In testimony whereof I have hereunto set my hand this 20th day of June, 1919.

EMIL HOTTINGER.
